MOLD COATING APPARATUS

Charles E. Smith, Three Rivers, Tex.

Application July 12, 1937, Serial No. 153,289

2 Claims. (Cl. 91—18)

This invention relates to an apparatus for producing carbon for coating molds, or what is commonly called a mold smoker, and its general object is to provide an apparatus that produces 5 carbon from oil, by burning the latter and which directs the carbonized gases in the form of smoke to the molds for the carbon to adhere thereto.

A further object is to provide an apparatus for 10 coating molds, that is capable of producing a maximum amount of carbon from a minimum amount of oil and fuel consumption, and also a quality of carbon that will readily adhere to the mold in the required quantities to bring about 15 perfect molded articles, such as glassware and the like.

Another object is to provide a mold coating apparatus that is simple in construction, inexpensive to manufacture and extremely efficient 20 in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding 30 parts throughout the several views, and in which:

Figure 1 is a vertical sectional view taken through the apparatus which forms the subject matter of the present invention, with parts in elevation.

Figure 2 is a sectional view taken approximately on line 2—2 of Figure 1, looking in the direction of the arrows.

Figure 3 is a view partly in section and illustrates one form of the conduit for conveying the 40 carbonized gases or smoke to a mold.

Referring to the drawing in detail, the reference numeral 1 indicates the body of my apparatus, which is shown as being in the form of a cylindrical casing, provided with a bottom wall 45 2, and the upper portion thereof is restricted to provide an annular shoulder 3 that merges into a relatively small neck 4.

The body is preferably supported by legs 5 which are secured to and depend from the bottom wall 2 thereof, as shown in Figure 1 and mounted within the body to be elevated above the wall 2, by legs 6 is a relatively flat annular fire pot 7 which has mounted therein and elevated above the bottom thereof, a burner 8, the latter being supplied with gas from a suitable

source of gas supply, by a pipe 9 which extends through the vertical walls of the pot and body or casing, as shown.

Superimposed with respect to the gas burner 8 and arranged in close proximity thereto is the outlet end 10 of a pipe 11 which has its outlet end curved downwardly for directing oil within the flame of the gas burner and the pipe 11 likewise extends through the vertical wall of the casing for disposal in communication with a suitable source of oil supply. The outlet end of the oil pipe may have a suitable nozzle thereon, but in any event the oil is supplied in a manner to drop upon the burner or within the flame thereof, so that it will be burnt to produce maximum amount of carbonized gas which rises from the fire pot and burner for disposal through the neck, as will be apparent.

The bottom wall 2 is provided with an opening within which is mounted a damper of the rotary type, in that it includes a slotted substantially conical wall 12 disposed below the bottom wall 2 and which has rotatably mounted thereon and shaped for fitting the same, a slotted closure member 13 for controlling the slots of the wall 12, it being obvious that the slots of the wall 12 may be completely or partially closed or fully opened by manipulating the closure member 13, and the latter may have a handle secured thereto. It will be noted that the conical wall 12 is formed on the lower end of the annular wall 14 of the damper and the wall 14 is fixed to a collar 15 that is secured about the edge of the opening.

In order to increase the draft action and to force the carbonized gas or smoke from the casing, I provide a pipe 16 that extends into the casing and has an upturned end 17 disposed within and concentrically with respect to the neck 4. The pipe extends through the wall of the casing as shown, and is disposed in communication with a suitable source of air under pressure.

Secured to the neck 4 is the lower end of a conduit 18, and for that purpose I provide a slip joint between the conduit and neck as well as a set screw 19. The conduit 18 in the form shown, 45 is of the goose-neck curved type and has detachably secured to the upper end thereof a mold receiving coupling or nozzle 20. While only one form of conduit is shown, and I want it understood that the conduits can be of any shape and 50 length suitable for the purpose, and couplings or nozzles of any size, may be applied thereto, so as to fit the molds of various sizes as will be apparent.

It is thought from the foregoing description 55

that the advantages and novel features of the invention will be readily apparent.

It is to be understood that changes may be made in the construction and in the combination and arrangement of the several parts, provided that such changes fall within the scope of the appended claims.

What I claim is:

1. A mold coating apparatus comprising a substantially cylindrical casing, a restricted upper portion for the casing, an outlet neck rising from said upper portion, gas burner means within the casing, means for depositing oil on the burner means to be burnt by the flame therefrom to provide carbonized gas, said oil depositing means having its outlet disposed directly above the burner means, a fire pot having the burner means mounted therein and supported above the bottom of the casing, draft means mounted in the bottom of the casing and disposed centrally below the fire pot, means for the passage of air under pressure into the neck and cooperating with the draft means to force the carbonized gas through the neck, a conduit detachably secured to the neck for conveying the carbonized gas from the cas-

ing, and a mold coupling detachably secured to the outer end of the conduit.

2. A mold coating apparatus comprising a substantially cylindrical casing having a closed bottom provided with an opening centrally arranged therein, a restricted upper portion for the casing, an outlet neck rising from said upper portion, gas burner means within the casing, means for depositing oil in the flame from the burner means to provide carbonized gas and disposed above and centrally of the burner means, a substantially flat annular fire pot provided with a closed bottom and having the burner means arranged centrally therein, legs supporting the fire pot above the bottom of the casing, adjustable draft means mounted in the opening for disposal centrally below the fire pot, means for the passage of air under pressure into the neck and cooperating with the draft means to force the carbonized gas through the neck, a conduit detachably secured to the neck for conveying the carbonized gas from the casing, and a mold coupling detachably secured to the upper end of the conduit.

CHARLES E. SMITH. 25
